(74) Attorney, Agent, or Firm—Knoble & Yoshida, LLC

(57) **CLAIM**

The ornamental design for a “handle for plastic container,” as shown and described.

DESCRIPTION

FIG. 1 is a perspective view showing a preferred embodiment of my new design;

FIG. 2 is a front elevational view;

FIG. 3 is a first side elevational view;

FIG. 4 is a rear elevational view;

FIG. 5 is a second side elevational view;

FIG. 6 is a top plan view; and,

FIG. 7 is a bottom plan view.

Any broken lines in the drawings depict probable environment only and form no part of the claimed design.
